Primary Examiner — Mitchell I. Siegel

(57) **CLAIM**

The ornamental design for a golf club head, as shown and
described.

DESCRIPTION

FIG. 1 is a front perspective view of a golf club head;
FIG. 2 is a rear perspective view of the golf club head of
FIG. 1;

FIG. 3 is a front elevational view of the golf club head of
FIG. 1;

FIG. 4 is a rear elevational view of the golf club head of FIG.
1;

FIG. 5 is a top view of the golf club head of FIG. 1;

FIG. 6 is a bottom view of the golf club head of FIG. 1;

FIG. 7 is a left side view of the golf club head of FIG. 1;

FIG. 8 is a right side view of the golf club head of FIG. 1;

FIG. 9 is a front perspective view of a golf club head;
FIG. 10 is a rear perspective view of the golf club head of
FIG. 9;

FIG. 11 is a front elevational view of the golf club head of
FIG. 9;

FIG. 12 is a rear elevational view of the golf club head of
FIG. 9;

FIG. 13 is a top view of the golf club head of FIG. 9;

FIG. 14 is a bottom view of the golf club head of FIG. 9;

FIG. 15 is a left side view of the golf club head of FIG. 9;
and,

FIG. 16 is a right side view of the golf club head of FIG. 9.
The broken lines shown are included for the purpose of
illustrating unclaimed subject matter and forms no part of
the claimed design.

1 Claim, 12 Drawing Sheets
